UNITED STATES PATENT OFFICE.

JOSEPH GORDON AND CHARLES R. PERKINS, OF PIONEER, OHIO.

FOLDING OR KNOCKDOWN BOX.

SPECIFICATION forming part of Letters Patent No. 477,051, dated June 14, 1892.

Application filed August 7, 1891. Serial No. 402,000. (No model.)

To all whom it may concern:

Be it known that we, JOSEPH GORDON and CHARLES R. PERKINS, both residents of Pioneer, in the county of Williams and State of Ohio, have invented certain new and useful Improvements in Folding or Knockdown Boxes; and we do hereby declare that the following is a full, clear, and exact description of the invention, which will enable others skilled in the art to which it appertains to make and use the same, reference being had to the accompanying drawings, which form a part of this specification.

Our invention relates to improvements in folding or knockdown boxes, generally employed for transporting eggs and produce, which are returned to the shipper after the articles contained therein are disposed of.

The object of the invention is to provide a simple, economical, and efficient construction of such a box, which can be easily and readily folded so as to occupy but little space and in which the fastening devices are protected from injury.

The invention consists in the novel construction and combination of parts hereinabove fully described, and specifically pointed out in the claim.

In the accompanying drawings, Figure 1 is a side view of a box constructed in accordance with our invention. Fig. 2 is a longitudinal section of the same. Fig. 3 is a central cross-section of the same. Fig. 4 is a horizontal section. Fig. 5 is a perspective view of the box partly folded.

In the said drawings, the reference-numeral 1 designates the base of the box, consisting of a rectangular board, to which are secured upwardly-projecting end strips 2 and side strips 3. Hinged to the supplemental end strip 2^a are the end pieces 4, capable of being folded down upon the bottom 1 and also of being elevated to a vertical position, according as the box is folded for transportation or storage or when knocked up to receive articles of produce.

The numeral 5 designates supplemental side strips placed alongside of the strips 3 and projecting above the same, one of said 50 supplemental strips being higher or projecting above the other. To these strips are

hinged the side pieces 6, which can be folded or elevated in a manner similar to the end pieces. The object of making one of the strips 5 higher than the other is to allow the piece hinged thereto to lie flat upon the opposite strip when folded, the latter resting in turn upon the end strips. The side pieces are provided with vertical grooves to receive a partition 7, and the end pieces are provided with upwardly-projecting pins 8, which pass through apertures in the cover, so as to hold the same in an elevated position. The cover consists of a rectangular board 9, having downwardly-depending end strips 10 and side strips 12, which are adapted to fit upon and embrace the upper ends of the hinged end and side pieces 4 and 6. Pivoted in central recesses 13 in the side strips 12 are hooks 14, adapted to engage with staples 15, secured to the outside of the side pieces 6, so as to hold the cover securely in place when the box is knocked up. The upper inner edges of the side strips 3 are formed with slots 16 and on their outer faces with intersecting recesses 17, in which are located staples 18, with which the hooks 14 engage when the box is folded or knocked down.

The operation will be readily understood. As seen in Figs. 1 and 4, the side and end pieces and partition are elevated, occupying vertical positions, and the cover in place and fastened by means of the hooks.

To fold or knock down the box, the cover is removed, the end and side pieces folded down, and the cover then placed thereon, as seen in Fig. 3, the hooks passing through the slots 16 and engaging with the staples 18, the recesses 17 being to allow the hook to be disengaged from the staples when it is desired to remove the cover.

From the above it will be seen that by the construction and arrangement of the hooks and the slots and recesses in the side strips said hooks are prevented from being injured, and not projecting beyond the box they cannot damage articles near by or injure persons in handling the boxes.

Having thus described our invention, what we claim is—

In a knockdown or folding box, the combination of the bottom having end strips, the

side strips having slots 16 in their upper edges and intersecting recesses 17, the supplemental end and side strips, the end and side pieces hinged thereto, the projecting pins on the end 5 pieces, the cover having apertures for the passage of said pins, the end strips, the side strips having recesses 13, the hooks 14, connected with said side strips, and the staples 15 and 18, substantially as described.

In testimony that we claim the foregoing as 10 our own we have hereunto affixed our signatures in presence of two witnesses.

JOSEPH GORDON.
CHARLES R. PERKINS.
